CLAIM

The ornamental design for ball glove shaping device, as shown and described.

DESCRIPTION

FIG. 1 is a perspective view of a ball glove shaping device showing my new design;

FIG. 2 is a right side elevational view thereof, left side being a mirror image;

FIG. 3 is a top plan view thereof;

FIG. 4 is a front elevational view thereof;

FIG. 5 is a rear elevational view thereof; and,

FIG. 6 is a bottom plan view thereof.

FIG. 1 is shown on an enlarged scale.
